UNITED STATES PATENT OFFICE

117,691

DESIGN FOR A BUILDING

Otis Horne, Atlanta, Ga.

Application July 25, 1939, Serial No. 86,227

Term of patent 3½ years

To all whom it may concern:

Be it known that I, Otis Horne, a citizen of the United States and resident of Atlanta, Fulton County, Georgia, have invented a new, original, and ornamental Design for a Building, of which the following is a specification, reference being had to the accompanying drawings, forming part thereof.

Fig. 1 is a front perspective view of a building showing my new design;

Fig. 2 is likewise a view in perspective taken from the side-rear;

Fig. 3 is a front elevational view;
Fig. 4 is a rear elevational view;
Fig. 5 is a top plan view;
Fig. 6 is an end view; and
Fig. 7 is an end view taken from the side opposite to that illustrated by Fig. 6.

I claim:

The ornamental design for a building, as shown.

OTIS HORNE.
